UNITED STATES PATENT OFFICE.

FREDERICK B. MALLORY, OF PORTLAND, OREGON.

DESIGN FOR A COMBINED SHACKLE, SWIVEL, AND CROSS-HEAD FOR BLOCKS.

43,847.

Specification for Design.

Patented Apr. 15, 1913.

Application filed January 31, 1912. Serial No. 674,617. Term of patent 7 years.

To all whom it may concern:

Be it known that I, FREDERICK B. MALLORY, a citizen of the United States, residing at Portland, in the county of Multnomah and State of Oregon, have invented a new, original, and ornamental Design for a Combined Shackle, Swivel, and Cross-Head for Blocks, of which the following is a specification.

The object of my invention is to provide a combination of the kind described that gives a finished appearance to the block to which it is attached.

In order to fully comprehend my invention reference must be had to the accompanying drawing, in which—

Figure 1 is a plan view of my invention. Fig. 2 is a front elevation of same, and Fig. 3 is a side elevation.

In order to designate and further explain my invention, letters and numerals of reference will be employed, in which the member designated by the numeral 1 is a cross-head to which swivel 2 is attached, and 3 is a shackle detachably fastened to swivel 2 by means of pin 4.

I claim—

The ornamental design for a combined shackle, swivel and cross-head for blocks as shown and described.

In testimony whereof I hereunto affix my signature in the presence of two witnesses.

F. B. MALLORY.
